(57) **CLAIM**

The ornamental design for a selfie stick, as shown and described.

DESCRIPTION

FIG. 1 is a top, front and left side perspective view of a selfie stick showing my new design;

FIG. 2 is a bottom, rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a top, front and left side perspective view showing the selfie stick in a state of use;

FIG. 10 is a top, front and left side perspective view showing the selfie stick in another state of use; and,

FIG. 11 is an enlarged view of portion 11 in FIG. 1.

The broken lines in the drawings illustrate portions of the selfie stick which form no part of the claimed design. The long dash-short dash broken lines illustrate the boundary of the enlarged views and form no part of the claimed design.
